CEMENT POT FOR USE IN CEMENTING
SOLES TO SHOE BOTTOMSWilliam S. Anderson, Philadelphia, Pa., assignor
to Shoe Press Corporation, Philadelphia, Pa.,
a corporation of Delaware

Application November 10, 1933. Serial No. 697,478

2 Claims. (Cl. 91—66)

This invention relates to cement pots and particularly to cement pots which have been designed for use when cementing soles to shoe bottoms. The device is specially advantageous for 5 the use of cobblers in repairing shoes by cementing soles to the shoe bottom, but it is also useful in shoe manufacturing establishments in which shoes are being manufactured with the soles cemented thereto.

- 10 In cementing a sole to a shoe a coating of cement is applied to the shoe bottom and also to the attaching face of the sole. The cement is frequently applied to the sole when the latter is made and sometime prior to its attachment to the shoe. In such case it is necessary to apply a 15 solvent or softener to the cemented face of the sole when the latter is to be attached to the shoe in order to give the sole a proper adhesive surface, and in order to do a good job in cementing a sole to a shoe it is important that the correct 20 amount of solvent or softener should be applied to the sole. In repairing a shoe by resoling it, it is also important that the right amount of cement should be applied to the shoe bottom before 25 the sole is attached. If an insufficient amount of cement is applied to the shoe bottom the sole will not adhere properly to the shoe and it is liable to peel off as the shoe is worn. If too much cement is applied to the shoe bottom the surplus 30 cement is liable to be squeezed out from between the sole and the shoe bottom when the pressure is applied to the sole, and the presence of such surplus cement is a source of annoyance and possible detriment.
- 35 In repairing shoes the cement is usually applied to the shoe bottom through the medium of a brush and the solvent or softener for softening the cement with which the attaching face of the sole has been provided is also usually applied 40 with a brush and, as stated above, the excellence of a job of resoling a shoe depends to a considerable extent upon using the correct amount of softener or solvent and the correct amount of cement.
- 45 The cement is usually applied around the marginal portion of the shoe bottom and the solvent is also applied around the marginal portion of the sole so that when the sole is cemented to the shoe the adhesive attachment is at the marginal portions of the shoe. The cement and the solvent which is used by cobblers is usually put up in tins and the present method is for the cobbler to pour out the cement and the solvent into 50 separate dishes and then to dip the brush into these dishes and apply the cement and the solvent to the shoe bottom and the sole respectively. With this method the amount of cement and solvent which is used on any shoe depends upon the judgment of the operator.
- 55 One object of the present invention is to pro-

vide a novel cement pot device which may be attached to the pouring opening of the cement-containing can and by means of which a uniform amount of cement will be transferred to the brush each time the latter is dipped into the cement pot, and this amount will preferably be such that one brushful of cement will provide the required amount of cement for use on one shoe. The same device is also applicable for applying the solvent so that the correct amount of solvent may be applied to soften properly the cement on the sole or shoe bottom and thus put both in condition for the cementing operation.

In order to give an understanding of the invention I have illustrated in the drawing a selected embodiment thereof which will now be described after which the novel features will be pointed out in the appended claims.

Fig. 1 is a view of the cement pot attachment device;

Fig. 2 is a view of the brush used for applying the cement or the solvent;

Fig. 3 illustrates a tin can such as the cement or solvent is usually put up in for sale to cobblers and the like;

Fig. 4 is a sectional view showing the cement pot attached to the can and the device in operation.

In the drawing 1 indicates a tin can of the type in which cement or solvent material for use in cementing soles to the bottoms of shoes is commonly put up for sale to cobblers. This tin can is shown as having the screw-threaded neck 2 which provides a pouring opening and which is adapted to be closed by a plug or closure 3 that is screw threaded into the neck.

The improved cement pot herein illustrated comprises a member 4 made of metal or any other suitable material which is formed with cement-receiving chamber 5 and with a suitable base 6 to rest on the table, floor or other support. The chamber 5 is open at the top as shown at 7 and is of a size to receive a brush 8 such as is commonly used for applying the cement to the bottom of a shoe or the solvent to the cemented face of the sole. This brush is provided with the usual handle 9.

The cement-containing member 4 is formed with a laterally-extending nipple 10 having an opening 11 therethrough which communicates with the cement-receiving chamber 5. This nipple is formed at its extremity to permit it to be attached to the neck 2 of the can 1. Where the neck is screw threaded as herein shown the end 55 of the nipple 10 will have the exteriorly screw-threaded portion 12 of the proper size and construction to screw into the neck 2 as shown in Fig. 4, a gasket or washer 13 preferably being employed to make a tight joint and prevent leak-

age around the screw threads when the device is used.

The position of the nipple 10 with reference to the base 6 is such that when said nipple has been 5 screw threaded into the neck 2 the base 6 stands substantially flush with the side wall 14 of the can.

In using the device the plug 3 is removed from the can and the member 4 is screwed into the 10 neck 2. The can may then be laid on its side as shown in Fig. 4 and this will allow the contents of the can to flow through the nipple 10 into the chamber 5. When the level of the liquid in the chamber 5 rises above the opening 10 any 15 further discharge of the contents of the can into the chamber 5 will cease because the liquid in the chamber 5 will prevent the admission of air into the can 1.

The brush 8 is provided with means for supporting it on the upper edge of the member 4 in 20 such a position that the bristles thereof will be partially submerged in the liquid in the well or chamber 5. The means herein shown for this purpose comprises a flange 15 rigid with the handle 25 of the brush and extending laterally therefrom and which is of sufficient size to form a cover for the open end 7 of the chamber 5. In fact, if desired, this flange portion 15 may be constructed so that it will make a sealed cover. The 30 flange herein shown is provided with a depending skirt 16 which encircles the top of the member 4 and it is also provided with inturned lips 17 which are set at a slight angle and which are adapted to engage underneath projections 18 35 with which the top of the member 4 is provided. 19 indicates a gasket or packing washer inside of the cap 15 which engages the top edge of the member 4.

The spacing between the lugs or projections 40 18 is sufficient to permit the lips 17 to pass between them and when the flange has been placed in position with the gasket 19 in engagement with the top edge of the member 4 a slight turning movement will operate to clamp the cap 2 to the member 4 because of the inclination of the lips 45 17. With this construction the level of the liquid in the chamber 5 will be kept approximately constant and hence each time that the brush is placed in the chamber 5 with the flange 15 resting 50 against the top edge of the member 4 the bristles of the brush will be submerged in the liquid to a predetermined point and it is not possible to dip the brush deeper into the liquid than is shown in Fig. 4.

Since the level of the liquid in the chamber 55 5 is maintained at a constant point and since the brush can be dipped into the liquid only to the extent determined by the flange or cover 15 it will follow that each time the brush is withdrawn from the chamber 5 it will carry 60 the same amount of liquid. As the liquid in the chamber 5 is used and the liquid level is lowered sufficiently to admit air into the can 1 through the passage 11 then there will be a transfer of liquid from the can into the chamber 5 65 sufficient to again choke the passage 11 and stop further flow so that, as stated above, the liquid level in the chamber 5 will be maintained substantially constant.

Assuming that the can is one containing cement. The size of the brush and the construction of the device may be such that the amount

of cement which is carried by the brush each time it is withdrawn from the chamber 5 will be just sufficient to cement properly the bottom of a shoe. On the other hand, if the can is one containing solvent the construction may be such that the amount of solvent which is carried by the brush when it is withdrawn from the chamber 5 will be just sufficient to properly soften the cement which has been previously applied to a sole. With this arrangement, therefore, a predetermined amount of cement will be carried by the brush each time it is withdrawn from the chamber 5, assuming, of course, that the brush has been dipped into the chamber as far as the flange 15 will permit. Hence with this invention a definite amount of liquid, whether it be cement or solvent, can be secured by simply dipping the brush into the chamber 5 as far as the flange 15 will permit and then withdrawing the brush and the danger of too scant or too liberal application of the cement or solvent due to ignorance or carelessness of the operator is avoided.

I claim:

1. A cement pot device for use with cement-containing cans, said device comprising a chambered member open at one end and closed at the opposite end, the chamber of which member constitutes a cement-receiving chamber, said member being formed with a laterally-extending nipple having provision for attachment to and detachment from the pouring opening of a cement-containing can and also being formed with a duct communicating with said chamber, the closed end of said member, when the latter is attached to the pouring opening of the can, being substantially flush with the side wall of the can, whereby when the can with the device so attached is placed on its side on a supporting surface with the open end of the cement-containing chamber directed upwardly the closed end of said device will rest on said surface and the cement level in said chamber resulting from the flow of cement thereinto through said nipple will be maintained substantially constant.

2. A cement pot device for use with cement-containing cans, said device comprising a chambered member open at one end and closed at the

opposite end, the chamber of which member constitutes a cement-receiving chamber, said member being formed with a laterally-extending

nipple having provision for attachment to and

detachment from the pouring opening of a cement-containing can and also being formed with

a duct communicating with said chamber, the

closed end of said member, when the latter is

attached to the pouring opening of the can, being

substantially flush with the side wall of the can,

whereby when the can with the device so attached

is placed on its side on a supporting surface with

the open end of the cement-containing chamber

directed upwardly the closed end of said device

will rest on said surface and the cement level

in said chamber resulting from the flow of cement

thereinto through said nipple will be maintained

substantially constant, in combination with a

brush adapted to be dipped into said chamber and

having a supporting flange adapted to rest on

the open top of said member and thereby limit the

extent to which the brush is submerged in the

liquid in the cement in the chamber.

WILLIAM S. ANDERSON.
